UNITED STATES PATENT OFFICE.

ALFRED M. DEMUTH, OF CHICAGO, ILLINOIS.

STEAM-TABLE.

1,356,518.

Specification of Letters Patent. Patented Oct. 26, 1920.

Application filed August 20, 1919. Serial No. 318,712.

To all whom it may concern:

Be it known that I, ALFRED M. DEMUTH, a citizen of the United States, residing at Chicago, in the county of Cook and State of Illinois, have invented certain new and useful Improvements in Steam-Tables, of which the following is a specification.

This invention relates to improvements in what is commonly termed steam tables, particularly adapted though not necessarily limited in its use for keeping hot or warm cooked articles of food and which table is so constructed and arranged that ready access may be had to the various articles and at the same time the steam or heating medium will not only be prevented from escaping but will also be prevented from coming into contact with the articles of food.

20 A further object is to provide an improved apparatus of this character whereby the heating medium will be confined within the table and maintained under a predetermined pressure.

25 To the attainment of these ends and the accomplishment of other new and useful objects as will appear the invention consists in the features of novelty in substantially the construction, combination and arrangement 30 of the several parts hereinafter more fully described and claimed and shown in the accompanying drawings illustrating this invention, and in which;

Figure 1 is a view partly in vertical section, partly in elevation and partly broken away of a table of this character constructed in accordance with the principles of this invention.

Fig. 2 is a top plan view of the same.

40 Fig. 3 is a detail view in elevation of the supporting rack.

Fig. 4 is an enlarged detail sectional view of a meat supporting block.

45 Fig. 5 is an enlarged sectional view of a detail.

Referring more particularly to the drawing, the numeral 10 designates generally the table which is supported in any suitable manner such as by means of legs or supports 11.

50 The table proper is in the form of a closed tank or receptacle of any desired size and configuration and is provided with any desired number of food chambers 13 which open through the upper wall or top 14 of the table and project thereinto for any de-

sired distance. The food chambers are of a size considerably less than the interior diameter of the table so as to permit the heating medium which is delivered into the 60 table to flow completely around the food compartments. These compartments may be of any desired configuration and are closed to the interior of the table so that steam or vapor from the heating medium 65 will not enter the food chambers nor commingle with the food.

Any desired heating medium may be employed but in the present form of the invention the interior of the table 10 is supplied 70 with water through the suitable opening closed by a suitable closure 16.

The food compartments are preferably of a rounded configuration at the bottom so as to form no obstructions or corners for 75 dirt.

Arranged to extend through the table is a pipe 17 of any desired size. The ends of the pipe project beyond the walls of the table as at 18 and are open. The open ends are 80 closed by suitable closures 19 so as to permit the pipe 17 to be cleaned by inserting an implement thereinto when the closures 19 are removed. The food chambers 13 are arranged in any suitable manner in the table 85 and any number or series thereof may be provided. One of these pipes 17 is preferably provided for each series and each of the food chambers has communication with the pipe 17 through the medium of a suitable 90 connection 20 which is preferably in the form of a sleeve or ferrule having a head or shoulder 21. The sleeve is adapted to be inserted through a suitable opening in the bottom of the food chamber so that the 95 head 21 will rest in a recessed portion 22 in the bottom of the chamber to permit the end of the sleeve to stand flush with the bottom of the chamber and prevent the formation of a shoulder. The other end of the 100 sleeve is threaded as at 23 into the pipe 17 so as to form a communication between the interior of the food chamber and the pipe. The pipe 17 is preferably arranged at an incline so that any liquid or matter which 105 may pass from the food chamber through the sleeve 20 and into the pipe 17 will gravitate toward the lower end of the pipe and be discharged therefrom.

The sleeve 20 is preferably provided with 110 internal threads 24 into which a closure 25, preferably in the form of a plug is adapted

to be screwed so as to cut off communication between the chamber and the pipe.

When it is desired to clean the chambers 13, all that is necessary is to remove the plug 25 and allow the matter in the chamber to pass out into the pipe 17, after which the chambers may be washed, the water finding its outlet through the sleeve 20.

If desired there may be provided a chamber 26 supported from the top 14 of the table and which chamber extends into the table, but is closed to the inside thereof. Within this chamber 26 may be arranged a meat supporting element or board 27 having a reinforcing band 28 countersunk into the edge thereof to prevent the board from splitting. The board is preferably of a size to project out of the chamber 26 and above the top 14 of the table and is adapted to receive meat or like food which is to be cut. This board may be provided with a depression 29 to receive the juices and which depression terminates in a well 30 so as to permit the juices to be removed when desired without removing the meat. A cover or bell 31 may be provided if desired.

Covers 32 may also be provided for the food chambers 13.

The heating medium 15 may be maintained at the desired temperature in any suitable manner. When it is desired to remove the water therefrom, this may be accomplished through the medium of a draw off cock 33 suitably arranged, and a water gage 34 may be provided to indicate the height of the water in the table. A thermometer may also be provided as well as a pressure gage 36 to indicate the pressure within the table. An automatic relief valve 37 and a safety blow off valve 38 may also be provided, and in order to form a convenient means for sliding a tray along the front or one side of the table, a suitable rack 39 may be provided and this rack may be supported by means of suitable brackets 40.

A shelf or support 41 may also be provided beneath the table for holding dishes or the covers 31—32 when the latter are removed.

With this improved construction it will be manifest that the food compartments are formed integral with the table and project thereinto, but are closed to the interior of the table so that steam or vapor will not mix with the food or escape from the table to burn or scald the attendant, while at the same time the food within the chamber will be maintained warm or hot and may be readily removed from the chambers.

By the provision of the drain pipe 17 which is common to all of the chambers of the respective series, it will be manifest

that any one or more of the chambers may be readily cleaned and washed out while the food remains in the other chambers.

Obviously if it is desired, a suitable heating apparatus such as a stove, burner or the like (not shown in the drawings) may be placed under the table to heat the water within the table.

In the present form of the invention two series of food chambers 13 have been shown and one drain pipe 17 is provided for each of the respective series. Obviously and if desired, drain pipes individual to the food chambers may be provided.

While the preferred form of the invention has been herein shown and described, it is to be understood that various changes may be made in the details of construction and in the combination and arrangement of the several parts within the scope of the claims, without departing from the spirit of this invention.

What is claimed as new is:—

1. A steam table of the character described embodying a tank or receptacle having a plurality of openings in one wall, a plurality of food chambers projecting into the receptacle, encompassing the respective openings, and being spaced from the remaining walls of the receptacle, said chambers being closed to the interior of the said receptacle, means whereby a heating fluid may be supplied to the receptacle, a closure for each of the food chambers, a conduit disposed below the chambers and opening through the wall of the tank, there being an outlet leading from the bottom of each of the chambers communicating with the conduit, means individual to the outlets for controlling them whereby the liquid may be drained from any one of the chambers, and means for controlling the conduit.

2. A steam table of the character described embodying a tank or receptacle having an opening in one wall, a food chamber projecting into the receptacle, encompassing the said opening, and being spaced from the remaining walls of the receptacle, said chamber being closed to the interior of the said receptacle, means whereby a heating fluid may be supplied to the receptacle, a conduit disposed below the said food chamber the opposite ends of the conduit being open to permit cleaning of the conduit closures for the openings in the conduit, there being a communicating passage between the chamber and the conduit, and means for controlling the said passage.

3. A steam table of the character described embodying a closed receptacle having a plurality of openings through one wall, food chambers within the receptacle and encompassing the respective openings, said chambers being spaced from the remaining walls of the receptacle, means for

introducing a heating medium into the receptacle, said heating medium being maintained under pressure around the chambers, a pressure gage, a conduit extending through 5 the receptacle and opening through the wall of the receptacle and into which conduit each of the chambers discharge, means individual to the chambers for controlling the communicating passage therebetween and 10 the conduit, and means for controlling outlet opening of the conduit.

4. A steam table of the character described embodying a closed receptacle having a portion shaped to form a comparatively shallow chamber extending into the receptacle and opening through one wall thereof, said chamber being closed to the interior of the receptacle and being spaced from the remaining walls of the receptacle, 15 and means for introducing a heating medium into the receptacle, in combination with a food supporting board or plate removably fitting said chamber and extending for a short distance beyond the adjacent 20 wall of the receptacle.

5. A steam table of the character described embodying a closed receptacle having a portion shaped to form a comparatively shallow chamber extending into the 25 receptacle and opening through one wall thereof, said chamber being closed to the interior of the receptacle and being spaced from the remaining walls of the receptacle and means for introducing a heating medium into the receptacle, in combination 30 with a food supporting board or plate removably fitting said chamber and extending for a short distance beyond the adjacent wall of the receptacle, the supporting surface 35 of said board being dished or cup shaped, and a removable cover adapted to be placed over the said board.

6. A steam table of the character described embodying a closed receptacle having a portion shaped to form food chambers extending into the receptacle and opening through one wall of the receptacle, said chambers being closed to the receptacle and spaced from the remaining walls of the receptacle, means for introducing a heating medium into the receptacle and around the chambers, a draw off connecting to the chambers and leading through the receptacle, means for controlling the draw off and 55 means individual to the chambers for controlling the discharge therefrom into the conduit.

7. A steam table of the character de-

scribed embodying a receptacle having an opening through one wall, a food chamber 60 encompassing the opening and extending into the receptacle, said chamber being spaced from the remaining walls of the receptacle and being closed to the interior of the receptacle, a cover for the chamber, 65 means for introducing a heating medium into the receptacle to be confined therein around the chamber, a conduit extending through opposite walls of the receptacle and having open ends, the said conduit being inclined and having connection with the interior of the chamber, and means forming 70 closures for the said open ends of the conduit.

8. A steam table of the character described embodying a receptacle having an opening through one wall, a food chamber encompassing the opening and extending into the receptacle, said chamber being spaced from the remaining walls of the receptacle and being closed to the interior of the receptacle, a cover for the chamber, 75 means for introducing a heating medium into the receptacle to be confined therein around the chamber, a conduit leading from 80 the chamber, the said conduit extending through opposite walls of the receptacle and being provided with openings accessible from the outside of the receptacle whereby the conduit may be cleaned, means forming 85 closures for the said openings in the conduit, and means for closing communication between the chamber and the said conduit.

9. A table of the character described embodying a closed tank having a plurality 90 of openings in one wall thereof, a receptacle projecting into the tank through each of the openings, said receptacles filling the respective openings and forming a closure therefor to prevent the escape of vapor 95 from the tank and around the receptacles, said receptacles being spaced from the remaining walls of the tank and being closed to the interior of the tank, a conduit arranged below and extending transversely of 100 the receptacles, said conduit being slightly inclined and having open ends, closures for the said ends of the conduit, and connections individual to the receptacles and forming communications between the conduit 105 and the respective receptacles.

In testimony whereof I have signed my name to this specification, on this 9th day of August, A. D. 1919.

ALFRED M. DEMUTH.
